(57) **CLAIM**

The ornamental design for a child swim vest, substantially as shown and described.

DESCRIPTION

FIG. 1 is a front, top perspective view of the child swim vest showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of the area labeled 8 in FIG. 1; and,

FIG. 9 is an enlarged view of the area labeled 9 in FIG. 4. The broken lines in the drawings illustrate portions of the child swim vest that form no part of the claimed design. The dot-dot broken lines shown along the perimeter of the child swim vest in FIGS. 1-7 illustrates seaming in the fabric. The dot-dash broken lines encircling portions of the child swim vest in FIG. 1, and illustrated in enlarged view in FIGS. 8 and 9 form no part of the claimed design.
